US0D1099371S

(12) **United States Design Patent** (10) **Patent No.:** **US D1,099,371 S**
(45) **Date of Patent:** **** Oct. 21, 2025**

(54) **APERTURED BUILDING PANEL**

(71) Applicant: **CertainTeed Ceilings Corporation**,
Malvern, PA (US)

(72) Inventors: **Samuel Carrillo Lacouture**,
Lawrenceville, GA (US); **Michael Magin**, Cumming, GA (US)

(73) Assignee: **CertainTeed Ceilings Corporation**,
Malvern, PA (US)

(**) Term: **15 Years**

(21) Appl. No.: **29/977,964**

(22) Filed: **Dec. 11, 2024**

Related U.S. Application Data

(62) Division of application No. 29/946,807, filed on Jun. 11, 2024, now Pat. No. Des. 1,060,747, which is a division of application No. 29/810,171, filed on Oct. 1, 2021, now Pat. No. Des. 1,035,922.
